RECOVERY OF HEMIMELLITENE

Stanley Francis Birch and Raymond Arthur Lowry, Sunbury-on-Thames, England, assignors to Anglo-Iranian Oil Company Limited, London, England, a British joint-stock corporation

No Drawing. Application September 30, 1944, Serial No. 556,672. In Great Britain October 19, 1943

7 Claims. (Cl. 260—674)

1

Hemimellitene (1,2,3-trimethylbenzene) one of the three trimethylbenzenes is difficult to obtain in a condition of purity. Hemimellitene occurs both in petroleum and in coal-tar, in a small proportion in relation to the other two isomeric trimethyl benzenes namely, mesitylene and pseudocumene, present. Careful fractionation however in highly efficient columns of either petroleum feedstocks, such as a liquid sulphur dioxide extract of heavy Iranian naphtha or a coal-tar distillate, (i. e. solvent naphtha), will yield a narrow boiling range fraction relatively rich in hemimellitene. The hemimellitene is however associated with a number of other hydrocarbons both aromatic and non-aromatic, of the same boiling range, and its separation from them is difficult. Although such a fraction from a product of petroleum origin (unless derived from a cracked or pyrogenic feedstock) would be substantially free from hydrindene, a similar fraction from a coal-tar naphtha would contain appreciable proportions of hydrindene, particularly if a preliminary mild hydrofining treatment to remove such unsaturated hydrocarbons as indene had been given to the coal-tar naphtha. Since the boiling points of hemimellitene and hydrindene are very close, the separation by fractionation alone, of hemimellitene from the hydrindene when present is practically impossible.

Known methods for the separation of hemimellitene from "concentrates" such as the fractions referred to, depend on fractional crystallisation and/or hydrolysis of the sulphonic acids or alkali sulphonates obtained by treatment with sulphuric acid. These methods are however tedious and do not lend themselves to the preparation of large quantities of the pure hydrocarbon.

Hemimellitene can be obtained by synthesis, but the most effective method of synthesis described in the literature is a lengthy operation and yields are small.

The invention consists in the recovery of the hemimellitene under the conditions hereinafter described by reference to the following table:

TABLE

Aromatic hydrocarbons boiling between 160° and 185° C. and those of the corresponding hydrogenation products

Aromatic Hydrocarbon	B. P., ° C.	B. P., ° C. after hydrogenation
m-Ethyltoluene	161.5	148-150.
p-Ethyltoluene	162.1	150-151.
Mesitylene	164.8	137-139.
o-Ethyltoluene	165.3	152-154.
tert. Butylbenzene	169.5	167-169.

Aromatic Hydrocarbon	B. P., ° C.	B. P., ° C. after hydrogenation
Pseudocumene	169.4	140-143.
Isobutylbenzene	172.8	170-172.
sec. Butylbenzene	173.5	178-179.
Hemimellitene	176.1	142-143.5.
1,2-Diethylbenzene	176.5	Not given.
m-Cymene	175.7	168-167.
o-Cymene	177	171.
p-Cymene	177.1	170.
Hydrindene	178.3	cis-166, trans-159.
1,3-Diethylbenzene	180.6	169-173.
n-Butylbenzene	183.1	179.
o-Propyltoluene	184	175-176.
m-Propyltoluene	182	170.
p-Propyltoluene	183	175.
1,4-Diethylbenzene	182	174-176.

15

It will be observed from the foregoing table in which are listed the boiling points of the aromatic hydrocarbons boiling between 160°-185° C. and the corresponding fully hydrogenated hexa-hydro-aromatics, (namely, the corresponding cyclohexanes), that the difference in boiling point between the trimethylbenzenes and their hydrogenation products is appreciably greater than those of the other aromatic hydrocarbons shown in the table, particularly those boiling in the same range.

It follows that if a narrow fraction boiling for example between 175° C. and 180° C., in which the hemimellitene has been concentrated by efficient fractionation, is fully hydrogenated by catalysis, re-fractionation of the hydrogenated product will yield a clear cut separation of the products derived from the trimethylbenzenes from those derived from other associated hydrocarbons of similar boiling range. Thus the hemimellitene boiling at 176° C. is converted into 1,2,3-trimethylcyclohexane which boils at 142° C. Any m-cymene (B. P. 175.7° C.) present under similar conditions would be converted into the corresponding cyclohexane which boils only 9° lower at 166°-167° C. Hydrindene when present is converted into cis and trans-bicyclononanes boiling at 166° and 159° respectively. Pseudocumene (B. P. 169.4° C.) when present is similarly converted into 1,2,4-trimethylcyclohexane which boils at 140° to 143° C., and would therefore be found associated with the naphthenes derived from the hemimellitene. If however the fraction derived from the hydrogenated product boiling between 140° and 145° C., that is to say, the fraction containing both the cyclohexanes derived from pseudocumene and hemimellitene is now reconverted to the original aromatic hydrocarbons by catalytic dehydrogenation, a product is obtained containing only pseudocumene and hemimellitene. Since these hy-

drocarbons boil at 7° apart their separation involves little difficulty.

Thus, by a series of operations comprising (1) fractionation, (2) hydrogenation, (3) fractionation, (4) dehydrogenation and (5) fractionation, it is possible to obtain hemimellitene in a pure state.

For the first hydrogenation of the aromatics to naphthalenes Raney nickel or other known hydrogenation catalysts may be used, provided the feedstock be sulphur free. Catalysts of the nickel-tungsten sulphide type may however be used if sulphur be present.

For the dehydrogenation reaction the hydrogenating catalyst, molybdenum oxide on alumina may be used, but the nickel-tungsten sulphide catalyst could also be used for this operation under more drastic conditions than those employed for the hydrogenation stage of the separation.

With sulphur-free feedstocks dehydrogenation may also be effected in the liquid phase by continued boiling in the presence of Raney nickel alone.

We claim:

1. In a process for the recovery of hemimellitene (1,2,3-trimethylbenzene) (B. P. 176.1° C.) from a narrow boiling range hydrocarbon oil fraction boiling between 175° C. and 180° C. which is relatively rich in hemimellitene and also contains a small proportion of pseudocumene (1,2,4-trimethylbenzene) (B. P. 169.3° C.) and a proportion of hydrindene (B. P. 178.3° C.) whose presence makes separation of hemimellitene by fractional distillation alone practically impossible, the steps of hydrogenating said narrow boiling range fraction by catalysis to convert the hemimellitene into 1,2,3-trimethylcyclohexane (B. P. 142° C.), the pseudocumene into 1,2,4-trimethylcyclohexane (B. P. 140°-143° C.) and the hydrindene into cis- and trans-bicyclononanes (B. P. 166° and 159° C., respectively); fractionally distilling the hydrogenated product to recover an intermediate fraction boiling between 140° and 145° C. containing only the trimethylcyclohexanes; dehydrogenating said intermediate fraction by catalysis to reconvert the cyclohexanes thereof into the original aromatic hydrocarbons to yield a dehydrogenated product containing only hemimellitene (B. P. 176.1° C.) and pseudocumene (B. P. 169.3° C.) readily separable by fractional distillation; and, fractionally distilling said dehydrogenated product to recover hemimellitene in a pure state.

2. The process of claim 1 in which said narrow boiling range fraction also contains m-cymene (B. P. 175.7° C.) which is converted by the hydrogenation into the corresponding fully saturated cyclohexane boiling at 166°-167° C.

3. In a process for the recovery of hemimellitene (1,2,3-trimethylbenzene) (B. P. 176.1° C.) from a narrow boiling range hydrocarbon oil fraction boiling between 175° C. and 180° C. which is relatively rich in hemimellitene and also contains a small proportion of pseudocumene (1,2,4-trimethylbenzene) (B. P. 169.3° C.) as well as a proportion of at least one other aromatic hydrocarbon so closely related in boiling point to hemimellitene as to make separation of hemimellitene therefrom by fractional distillation

alone practically impossible and hydrogenatable to a fully saturated cyclohexane derivative having a boiling point outside the range 140° C. to 145° C., the steps of hydrogenating said narrow boiling range fraction by catalysis to convert hemimellitene, pseudocumene and said other aromatic hydrocarbon present to their corresponding fully saturated cyclohexane derivatives; fractionally distilling the hydrogenated product to recover an intermediate fraction boiling between 140° C. and 145° C. containing only the relatively low boiling cyclohexane derivatives of said trimethylbenzenes; dehydrogenating said intermediate fraction by catalysis to reconvert the cyclohexanes thereof into the original aromatic hydrocarbons to yield a dehydrogenated product containing only hemimellitene and pseudocumene, readily separable by fractional distillation; and, fractionally distilling said dehydrogenated product to recover hemimellitene in a pure state.

4. The process as specified in claim 1 further characterised in that a hydrogenation catalyst of the nickel-tungsten sulphide type is used when sulphur is present in the feedstock.

5. The process as specified in claim 1 further characterised in that a hydrogenation catalyst of the Raney nickel type is used when the feedstock is sulphur free.

6. The process as specified in claim 1, in which the fraction derived from the hydrogenated product, boiling between 140°-145° C., containing both the cyclohexanes derived from pseudocumene (B. P. 169.4), and hemimellitene (B. P. 176) is subjected to catalytic dehydrogenation using molybdenum oxide on alumina under dehydrogenating conditions as catalyst and the fraction thus re-converted into the original aromatic hydrocarbons, to yield the product containing only pseudocumene (B. P. 169.4) and hemimellitene (B. P. 176) readily separable by fractionation.

7. The process as specified in claim 1 in which the fraction derived from the hydrogenated product, boiling between 140°-145° C., containing both the cyclohexanes derived from pseudocumene (B. P. 169.4), and hemimellitene (B. P. 176) is subjected to catalytic dehydrogenation using as catalyst a nickel-tungsten sulphide type catalyst under dehydrogenating conditions more drastic than the hydrogenating conditions employed when using the same nickel-sulphide type catalyst in the hydrogenation stage and the fraction thus re-converted into the original aromatic hydrocarbons, to yield the product containing only pseudocumene (B. P. 169.4) and hemimellitene (B. P. 176) readily separable by fractionation.
